CLAIM

U.S. PATENT DOCUMENTS

The ornamental design for the stencil brush having pillared bristles, as shown and described.

DESCRIPTION

1,789,627 A * 1/1931 Hill 15/210.5
3,964,122 A * 6/1976 Kurdy ..... 15/DIG. 5 X
4,483,036 A * 11/1984 Sayklay 15/160
D288,987 S * 3/1987 Bambury D4/127

FIG. 1 is a perspective view of a stencil brush having pillared bristles showing my new design, the broken lines showing a ferrule and handle being for illustrative purposes only and forming no part of the claimed design.

FIG. 2 is a top plan view thereof; and,

FIG. 3 is a right side view of FIG. 1, of which the left, front and back side views are mirror images.
